and five percent to Frank Bruno, both of East
Chicago, Ind.

Application April 20, 1937, Serial No. 137,970

2 Claims. (Cl. 156—39)

This invention relates to a novel automatically operating window screening device.

One of the main objects of this invention is to provide a window screening device which is automatically operated by the opening of the window, so as to extend across the window opening for properly screening the same; and which is again automatically retracted by the closing of the window.

Another object of this invention is to provide such a screening device which is compact and durable in construction, and is efficient in use, and which at the same time presents a neat appearance.

These and various other objects and advantages are attained with this invention, as will become apparent from the following description, taken in connection with the accompanying drawing in which this invention is illustrated in its preferred form of construction; it being understood that various other arrangements and forms of construction may be resorted to for carrying out the objects and purposes of this invention.

In the drawing:

Fig. 1 is an elevational view of the device, parts being in section and parts being broken away, and

Fig. 2 is a partial perspective view of the screen roll.

In the drawing my invention is illustrated in its preferred form of construction, and it is herein shown mounted between the lower parts of the side frame members or jambs 11 of the window frame, adjacent the lower frame member or window sill 12, for screening the lower window opening. This device can likewise be applied to the upper window sash for screening the upper window opening.

This device comprises a cylindrical roll 17, which preferably includes an outer member 18 and an inner member 19 telescoped therein, to enable adjusting the roll to the desired length. The roll is slotted longitudinally, and the screen 21 has its end part inserted in the slit and secured in position. This is preferably done by means of a curved doubled member 22 which has the screen enter thru its mouth portion outside of the roll and extend into its toe portion 22' inside of the roll, while a heel 22" bears under the edge of the roll, thereby securely clamping the screen edge therein, as indicated in the drawing. The two parts 18 and 19 of the roll are readily telescoped together and slid upon member 22 with the screen therein, being thus adapted to fit

screens of various widths, and also to prevent the one roll part from turning on the other.

The means provided for rotating the screen roll in the window frame comprises a pair of axle means 23, one positioned at each end of the roll, 5 and a washer 24 secured in each end of the roll, adapted to rotate on the axle means 23. Said means 23 includes an axle portion or neck 25 whereon the washer rotates having an integral flange 26 at the inner end thereof engaging 10 against the inner side of the washer. A head plate 27 is fastened removably to the outer side of portion 25, as by suitable screws; and a rectangular post 29 extends outwardly from said head plate and is mounted in a rectangular portion 30 of a bracket 31 which is secured to the jamb 11. The bracket 32 at the other side of the roll may be similar in construction or may be in the form of a disc secured to jamb 11 and having a rectangular opening therein to receive 20 the opposite post 29 of the roll to hold the axle members against turning. A stem 33 extends inwardly from axle portion 25, and carries a coil spring 34 thereon which has one end secured to the stem and has the other end secured to the 25 roll, whereby this spring is coiled tighter on the stem as the screen is unrolled with the opening of the window. The head plate 27 is detachable from axle portion 25 for the purpose of assembling the members. 30

The free end of the screen is suitably attached to the adjacent bar of the window sash to travel therewith.

The two side edge portions of the screen travel in guide channels 40 mounted on jambs 11, closely 35 adjacent the window sash.

Means is provided to cover the space between the sill 12, and the roll when unwound, and this means includes a guide roller 43 which is positioned closely adjacent to sill 12 and has end pins 40 rotatably mounted in bearing means 44 secured to jambs 11. The screen 21 thus passes from the screen roll under this guide roller and then upwardly, so that it will always be held closely adjacent to sill 12 when the screen roll is unwound 45 as well as when it is wound.

I claim:

1. A window screening device mountable in a window frame, said device comprising a screen and a roller containing two telescoping portions 50 adjustable for length and slotted longitudinally, and a doubled strip clamped over one end of the screen and together therewith extending thru the slit, said strip including oppositely extending means engaging the interior of the roller ad- 55

jacent the slit and holding the strip and screen securely in position.

2. A window screening device mountable in a window frame, said device comprising a screen and a roller consisting of two telescoping cylindrical portions clamped tightly together but being separable and adjustable for length and provided with a longitudinal slit, and a curved dou-

bled strip clamped over one end of the screen and together therewith extending thru the slit, said strip including oppositely projecting toe and heel portions engaging the interior marginal portions of the roller alongside the slit, to hold the strip and screen securely in position therein.

FRANK KUSHNER.
